REPLACEMENT TYPE DUAL VARIABLE RESISTOR

Karl W. Youngbeck, Milwaukee, Wis., assignor to Globe-Union Inc., Milwaukee, Wis., a corporation of Delaware

Application December 24, 1953, Serial No. 400,285

1 Claim. (Cl. 201—55)

This invention relates to dual variable resistors of the replacement type.

In order to replace custom dual controls in radio and television receivers a jobber would have to carry in the neighborhood of 400 different custom units to have a complete line. This is very unwieldy and expensive.

It is an object of this invention, therefore, to provide a replacement type dual variable resistor which is easily and quickly made by the serviceman to match the electrical characteristics of the custom control to be replaced by selecting separate controls, measuring and cutting off their shafts and making a dual unit by merely snapping such separate controls together.

A jobber needs only maintain in stock in the neighborhood of 50 different completed separate controls with one type of shaft and a like number of completed separate controls with another type of shaft in order to supply to the serviceman enough combinations of controls to enable him to make replacements for approximately 400 different custom dual units. The front section control employs a sleeve shaft and the rear section control uses a small shaft which mounts concentrically in the sleeve shaft. The electrical characteristics of each separate control are varied by using different resistances. However, the resistors and rotors are of well known design. The front control section has a mounting bushing of conventional design by which the assembled dual unit is secured to a panel or chassis. The rear control section has a mounting cap which fits over the housing of the front control section and is snapped in place by tooth and notch means cooperating between such cap and the housing of the front control section. After selecting each section to match the electrical characteristics of the replaced custom dual control, the serviceman measures the length of the shafts of such custom control from the face of its mounting bushing and applies such measurements to the sleeve shaft of the front control and to the small shaft of the rear control. The small shaft has a visible groove on the surface thereof which in the assembled condition of the sections is in alignment with the face of the mounting bushing and this is used to apply the measurement from the custom unit. The shaft for the rear section has a standard flat which will permit a variety of sizes of knobs to fit thereon. The sleeve shaft of the front section has standard flats so that a knob designed to fit a slot can be fitted thereon. These flats have milled grooves in the surface thereof which act as guides to cut slots in such sleeve shaft so that it will accommodate knobs which are designed to fit on slotted shafts. When the shafts have been cut to length and the sleeve shaft slotted, if necessary, the small shaft is fitted into the sleeve shaft and the sections snapped together to make the unit.

The characteristics and applications of this invention may be best understood from the following description of a specific embodiment when read in connection with the accompanying drawings, in which:

Fig. 1 is a view in side elevation, with parts broken away

2

and shown in section, of a replacement type dual variable resistor embodying the present invention;

Fig. 2 is an isometric exploded view of the rear section mounting cap and bushing forming a part of this invention;

Fig. 3 is an enlarged sectional view taken on the line 3—3 of Fig. 1; and

Fig. 4 is an enlarged sectional view taken on the line 4—4 of Fig. 1.

In the embodiment of the invention shown in the drawing the replacement type dual variable resistor has a front (to the left) control section 10 and a rear control section 12 which, when joined as shown in Fig. 1, make a dual unit which may be mounted to a panel so that each unit is separately operated by its own shaft. Each section has a resistance over which a rotor moves. By varying the value of the resistance a large range of sections may be obtained from which a great number of combinations may be made. The mechanical construction of each control section is identical and well known to those skilled in this art except for the mounting cap of the rear section and the external part of the operating shafts.

Each section has an insulating base 14 on which are mounted terminal 16. Each has a cover with annular side walls 18 and flat rear wall 20. The latter has a central opening 22 therein to provide operating access to the control shaft from the rear. A bead 24 is formed in the side wall 18 which is used in properly angularly relating the front and rear sections and any switch which might be added to the rear section. The side wall 18 also has opposite related teeth 26 which engage with notches in the manner hereinafter described to connect the sections with a snap action. Dimples 28 formed in the rear wall 20 are used to slightly deflect such wall when the sections are snapped together and provide resilient bias to hold the snap lock tight.

The front section 10 has a threaded mounting bushing 30 to which the cover 18 is secured by tabs 32. A sleeve shaft 34 is rotatably mounted in the bushing 30 and connected to the rotor by peening over end lugs 36. It is preferable to provide the sleeve shaft with a counterbore 38 to make the lugs 36 thinner and easier to bend without breaking. That portion of the shaft extending outwardly of the bushing 30 has a pair of opposed flats 40 (see Fig. 3). These flats will permit various sized knobs designed to fit on flats to be mounted on the sleeve shaft 34. In the face of each of these flats are spaced guide grooves 42. These grooves assist in cutting a slot in one or both of the flats 40, whenever it is necessary to mount a knob on the sleeve shaft 34 which is designed to fit on a slotted shaft. The length of the sleeve shaft 34 is long enough to cover all custom units which this replacement unit is designed to replace. When the custom unit is removed both its shafts are measured from the face of its mounting bushing. The sleeve shaft measurement may be applied to sleeve shaft 34 before the rear section is assembled and the sleeve shaft 34 cut. The sleeve shaft 34 is held in proper position within the bushing 30 by a C-ring 44 which fits in an annular groove in the outer surface of the shaft. The front section when assembled with its sleeve shaft 34 constitutes a complete separate and independently variable resistance. It is possible to make in the neighborhood of 50 front sections which vary only in their electrical ranges.

The rear control section 12 has an intermediate mounting cap 46 with an annular wall 48 which slidably fits over the side wall 18 of the front control section. The annular wall 48 is provided with a channel 52 which fits over the bead 24 to angularly locate the front and rear sections. Notches 54 in the annular wall 48 receive the teeth 26 on the front section and lock the mounting cap 46 in place.

Laterally deformed lips 56 on the periphery of the wall 48 permit the insertion under the wall of a small screw driver or other like instrumentality to pry the edges of the notches 54 out of contact with the teeth 26 to disassemble the front and rear sections. The end wall 50 has a central opening 58 provided with notches 59. A bushing 60 is fitted in such opening and staked in such notches with its rear end projecting beyond the end wall 50 into an opening 62 in the base plate 14 to centralize such plate and the mounting cap 46. As is most clearly shown in Fig. 2, the end wall 50 has a pair of diametrically arranged rearwardly projecting pads 64 which provide seats for the base plate 14. A plurality of rectangular openings 66 in the periphery of such pads permit the tabs 32 to enter into the side of the cap 46 and be bent over on the inner face of the pads 64 so that the mounting cap may be securely held to the rear section 12. A small rear section shaft 68 is rotatably carried in the bushing 60 and connected in customary manner to the rotatable part of the rear section. This shaft has a flat inner end 76 which is in axial alignment with the central opening 22. This flat end may be connected with the coupler of a line control switch which can be mounted on the rear section. The shaft 68 is held in place by a C-ring 72 fitting in a groove in such shaft and bearing against the bushing 60. The extended forward end of the shaft 68 projects coaxially through the sleeve shaft 34 and has a standard flat 74. This standard flat will take several sizes of knobs designed to fit on standard flat shafts. When knobs designed to fit on knurled shafts need be fitted on the shaft 68 a spring clip insert (not shown) of standard design is fitted between the flat 74 and the knob. The length of the shaft 68 is such that it will be long enough to fit in all situations where this type of control is used as a replacement. The required length of the inner shaft 68 is measured from an annular notch 76 so located longitudinally on such shaft as to be in alignment with the face of the mounting bushing 30 when the rear section 12 is properly assembled to the front section.

When both the sleeve shaft 34 of the front section 10 and the small shaft 68 of the rear section 12 have been cut to length to match the length of the shafts of the custom unit, and the sleeve shaft 34 slotted if necessary, the rear section 12 is assembled to the front section by

inserting the shaft 68 through the rear opening 22 into the sleeve shaft 34. With the channel 52 alined with the bead 24 the rear section 12 is pressed forwardly on the front section 10 until the teeth 26 snap into the notches 54. 5 The flat rear wall 20 of the front section will be slightly depressed by the engagement between the dimples 28 and the forward face of the bushing 60. This will create a resilient bias to apply pressure between the teeth 26 and the notches 54 and hold the section securely in place without relative movement. To disconnect the rear section from the front section a screw driver or a like instrument is inserted under the lip 56 to raise the edge of the notch 54 out of engagement with the tooth 26.

10 In the neighborhood of 50 front and 50 rear sections can be made each of which vary in its electrical characteristics but are of the same physical dimensions and mechanical construction. Any one of the rear sections can be fitted on any one of the front sections in the manner just described to make in excess of the number of combinations required for replacements. The serviceman can therefore make a wide variety of combinations of replacement type dual variable resistors to replace custom units made to manufacturer's specifications.

15 What I claim and desire to secure by this patent is: 25 A multiple unit control of the replacement type, comprising a first unit having a mounting face for engagement with a panel and a sleeve shaft rotatably mounted therein and extending outwardly of said mounting face, and a second unit adapted to be snap-fitted onto said first unit and 30 having a small shaft extending through said sleeve shaft and projecting outwardly thereof, the outwardly projecting portion of said sleeve shaft having a pair of opposed flats with spaced grooves cut in from the faces of said flats and extending longitudinally thereof, the grooves in 35 one flat being alined with the grooves in the other flat so that said sleeve shaft may be conveniently cut to provide a slotted end.
